United States Patent Office

Des. 231,609

Patented May 7, 1974

231,609

OPTICAL ELECTROPHORESIS SCANNER

Jan A. Vanden Brook, Ann Arbor, and George W. Toma, Dexter, Mich., assignors to Transidyne General Corporation, Ann Arbor, Mich.

Continuation-in-part of design application Ser. No. 149,133, June 1, 1971, now Patent No. 225,990. This application Oct. 19, 1972, Ser. No. 298,968

Term of patent 14 years

Int. Cl. D24—02

U.S. Cl. D16—2 C

Fig. 1

Fig. 2

Fig. 3

FIG. 1 is a front elevational view of an optical electrophoresis scanner showing our new design;

FIG. 2 is an elevation as seen in the direction of line 2—2 of FIG. 1.

FIG. 3 is a front and right side perspective view thereof. The rear, not shown, is substantially plain and unornamented.

This is a continuation-in-part of design application Ser. No. D. 149,133, filed June 1, 1971 and now Pat. No. D. 225,990.

We claim:

The ornamental design for an optical electrophoresis scanner, as shown and described.
